CLAIM

The ornamental design for a trash can, as shown and described.

DESCRIPTION

FIG. 1 is a top, front, left-side perspective view of a trash can embodying our design;

FIG. 2 is a front elevation view thereof;

FIG. 3 is a rear elevation view thereof;

FIG. 4 is a right-side elevation view thereof, the left-side elevation view being a mirror image of the right-side elevation view;

FIG. 5 is a top plan view thereof; and,

FIG. 6 is a bottom plan view thereof.

The broken line shown in FIG. 3 is included for the purpose of illustrating portions of the trash can and forms no part of the claimed design.
